Specification for Design.

Patented Sept. 25, 1917.

Application filed June 13, 1917. Serial No. 174,631. Term of patent 14 years.

To all whom it may concern:

Be it known that I, ESTEN B. BEELER, a citizen of the United States, and a resident of the city, county, and State of New York, have invented a new, original, and ornamental Design for a Humidifier, of which the following is a specification, reference being had to the accompanying drawing, forming a part thereof.

Copies of this patent may be obtained for five cents each, by addressing the "Commissioner of Patents, Washington, D. C."

Fig. 2 is a side view thereof.

I claim:

The ornamental design for a humidifier, as shown.

In testimony whereof, I have signed my name to this specification this eleventh day of June, 1917.

ESTEN B. BEELER.
